3 Sheets-Sheet 3

UNITED STATES PATENT OFFICE.

FRED L. MARK, DECEASED, LATE OF CHICAGO, ILLINOIS; BY HELENE D. MARK,
ADMINISTRATRIX.

CUTTING MACHINE.

Application filed August 16, 1922. Serial No. 582,139.

To all whom it may concern:

Be it known that FRED L. MARK, deceased, a citizen of the United States, formerly residing at Chicago, County of Cook, and State 5 of Illinois, has invented a certain new and useful Improvement in Cutting Machines, of which the following is a specification.

This invention relates to cutting machines in general, but more particularly to 10 machines for cutting cloth or other sheet material, and more especially to machinery for cutting discs or other small sections of cloth from the sheet while the latter is maintained in a flat and stretched condition, 15 and preferably with one sheet superposed upon another, so that a plurality of layers can be cut at the same time.

Generally stated, therefore, the object of 20 the invention is to provide a novel and improved construction whereby cloth or other sheet material can be cut or subdivided into discs or other small sections, in a convenient and economical manner, with as little waste as possible, and whereby a plurality 25 of layers of cloth or other sheet material can be cut at the same time, for any desired purpose, but more particularly for the purpose of cutting out small discs of cloth which can be used in the manufacture of 30 powder puffs or other similar articles, as will hereinafter more fully appear.

It is also an object to provide certain details and features of construction and combinations tending to increase the general 35 efficiency and the desirability of a cutting machine of this particular character.

To the foregoing and other useful ends the invention consists in matters hereinafter set forth and claimed and shown in the accompanying drawings in which—

Figure 1 is a plan of a cutting machine embodying the principles of the invention, with certain intermediate portions thereof shown broken away for convenience of illustration.

Figure 2 is a side elevation of the machine shown in Figure 1.

Figure 3 is a front end elevation of the said machine.

Figure 4 is an enlarged detail section, 50 vertically and longitudinally of the machine, on line 4—4 in Figure 3.

Figure 5 is an enlarged detail section on line 5—5 in Figure 2.

Figure 6 is an enlarged transverse section on line 6—6 in Figure 2. 55

Figure 7 is a side elevation of a portion of the structure shown in Figure 6.

Figure 8 is a detail vertical section on line 8—8 in Figure 6.

Figure 9 is an enlarged detail section on line 9—9 in Figure 1. 60

Figure 10 is an inside elevation of the structure shown in Figure 9, and

Figure 11 is a plan of the structure illustrated by Figures 9 and 10. 65

As thus illustrated, the invention comprises a table-like structure having a rigid frame 1 supported at a suitable height by the legs 2 which rests on the floor. The side portions 3 are in the nature of brackets and are adjustable up and down on said frame by reason of the slots and nuts 4 provided thereon, and the upper ends of these brackets have notches 5 along their upper edges. A swinging support 6 is provided with a rigid 70 transverse member 7 having pins or trunnions 8 adapted to engage the notches 5, whereby said support 6 is adapted to swing up and down about a transverse axis. The ring-like or annular member 9 has teeth 10 for 75 engaging the cloth, as will hereinafter more fully appear, and is mounted upon a supplemental swinging support 11 which is pivoted upon the under side of said other support at 12, and which is normally locked in raised 80 position by a small latch or catch 13 of any suitable character. This ring-like member 9 is provided with a handle 14 by which it may be raised and lowered. The rotary 85 and cylindrical cutter 15 is carried on the lower end of a spindle or shaft 16 carried by the bearings 17 provided on the front end of the support 6, whereby this cutter is adapted to extend through and rotate within the ring-like member 9 previously described. A motor 18 is mounted on the rear end of the support 6 to operate said cutter, and for this purpose the upper end of 90 said shaft is provided with a pulley wheel 19 connected by a belt 20 to said motor. The motor over balances the cutter, so that the latter is normally in raised position, and to limit this upward movement of the cutter the swinging support 6 has a portion 95 21 to engage the stationary stop 22 swivelly mounted on the body frame of the machine.

Any suitable means can be employed for supplying electric current to said motor. A handle 23 is secured to the outer end of the head 24 of the swinging support 6, and with this arrangement the supports 6 and 11 can be swung up and down together or separately.

The means for holding the cloth are as follows: The side portions of the main body frame are provided with parallel and longitudinally extending guides 25 which are carried by adjusting screw devices 26, of any suitable character, whereby these guides can be moved toward and away from each other for different widths of cloth. The cloth holding frame 27 is slidable back and forth on these guides, and is provided with metal portions 28 to receive the cloth clamping bars 29 which have teeth 30 to pierce and hold the cloth. The metal strips 31 are mounted on top of the cloth holding frame 27, and are provided with teeth 32 for engaging the cloth. It will be seen that the various layers of cloth 33 are clamped between the bars 29, and it will be seen that the metal clamping jaws 33 are applied to the upper edges of the cloth holding frame and held in place by bolts to compress the superposed layers of cloth and bars 29 to tightly hold the cloth horizontal in stretched condition. The cloth is not held at the front end of the machine, but at the rear end of the cloth holding frame 27 there are metal holding devices 35, and the bars 36 have metal portions 37 to engage the metal elements 35, in the manner shown in the drawings, so that the bars 36 are held one above the other transversely of the machine. Teeth 38 are provided on the bars 36, to pierce and hold the cloth, and a metal strip 39 is secured to the lower edge of the cloth frame and provided with teeth 40 to engage the cloth. Thumb buttons 41 are provided on the cloth frame to hold the bars 36 down, so that the cloth will be maintained in stretched condition. This frame 27 upon which the cloth is thus mounted and held horizontally is adapted to slide longitudinally of the machine, and is for this purpose provided with an internally threaded sleeve 42 which travels like a nut on the threaded rod 43, which latter extends longitudinally of the machine, below the cloth, and is supported by bearings 44 at the front and rear ends of the stationary body frame of the machine. Said threaded rod 43 is provided at its front end with a handle or crank 45 for rotation of the rod to move the cloth frame and the cloth back and forth longitudinally of the machine whenever such is necessary or desirable.

Now the operator sits in the space 46 at the front end of the machine, where the three handles 14, 23 and 45 are easily reached, and where the cloth extends over

the stationary bed or cutting table 47 carried by the stationary body frame. It will also be seen that the pivoted or swinging support 6 is provided with a vertical swivel 48 whereby the cutter 15 and its toothed holding ring 9 may be swung from side to side, in the manner shown in dotted lines in Figure 1, whereby it is possible to place said cutter and holding ring on any portion of the cloth. The operator first unlatches the support 11, and lowers the latter by the handle 14 until the teeth 10 engage the section of the cloth to be cut. Then the operator pulls down on the handle or manual-actuator 23 to lower the cutter into engagement with the section of cloth thus held by the teeth 10, and downward pressure forces the cutter through the different layers of the cloth and into engagement with the table 47, thus cutting out several discs of cloth. It will be understood that the shaft 16, and also the swivel 48, are approximately vertical when the cutter is thus lowered into operative position. The table 47 is preferably of some material which will not dull the edge of the cutter. The cutter is rotated at high speed, by the motor 18, during this cutting operation. The operator then releases the handle 23, allowing the cutter to rise, and then shifts the holding ring 9 on to a different spot on the cloth, and the cutting operation is then repeated. Cutters of different sizes can be employed for making large or small discs of cloth, as may be desired. Adjustment of the trunnions 8 from one notch to another is possible if such is necessary or desirable. Also, as stated, the cutting action can be regulated to ensure the desired result by vertical adjustment of the brackets 3 previously mentioned. With this arrangement the operator can cut discs from the cloth, with as little waste as possible, and with ease and convenience and with very little expense for power to drive the cutter. When the cloth is all reduced to discs, by the repeated operation of the cutter, the cutting means are then raised and latched in raised position as shown in Figure 2, and the residue of the cloth is removed from the cloth frame and fresh sheets of layers of cloth are inserted.

It will be seen that a cutting machine of this kind can be used for any suitable or desired purpose. For example, it can be used for cutting cloth in the manner shown and described, in the manufacture of powder puffs, the discs of cloth being sewed or fastened together to produce the desired article or product of manufacture. The cutting means are power driven, but are manually controllable and adapted to be manipulated at will by the manual actuator 23 to place the annular cutting edge exactly where wanted on the cloth. Thus the cutter is moved about from one place to another by

the same power by which it is pressed against and through the cloth, for both functions are performed by the handle 23, very obviously, in the manner explained. 5 Shifting of cloth is also manually controlled, so that as fast as the cloth is cut into discs, by swinging the cutter transversely, the cloth as a whole can be pulled forward to bring fresh sections thereof within the 10 operative range of the cutter.

In the lateral adjustment of the two sides of the frame 27, by adjusting the guides 25, as previously described, it will be seen that some provisions are necessary for the trans- 15 verse rear end of the cloth holding frame, in order to permit of this adjustment. As shown, therefore, the rear end portion of the cloth holding frame is provided with L-shaped brackets 48 having slots 49, and the 20 transverse rear portion 50 of the frame is supported by bolts 51 which are slideable in these slots. In this way, therefore, the rear end portion 50 of the frame is normally rigid with the sides thereof, but may be 25 loosened by turning the nuts of the bolts 51 when it is desired to adjust the two sides of the frame toward or away from each other.

Of course, in reloading the machine with 30 fresh sheets of cloth, the bars having the sharp points are removed upwardly, from the inside surfaces of the movable cloth frame, and then fresh layers of cloth are placed in position, and some of the bars are then placed on top of the cloth, and then 35 more cloth and more bars, as shown, until the machine is again ready for another series of cutting operations to reduce the cloth to discs of the desired character.

It will be seen that the mounting of the 40 motor 8 on the support 6 simplifies the problem of driving the cutter, as no complicated driving arrangement is required, such as might be necessary if the motor were mounted on the body frame of the machine, 45 or on the floor below. With the arrangement shown, the motor and the cutter are mounted on the same movable support, and the motor is moved around by the shifting of the cutter. Furthermore, it will be seen 50 that the cutter has a limited range of operation, of course, and that for this reason the cloth is supported by means for presenting successive sections of the cloth to the cutter, or for causing successive sections 55 of the cloth to be brought within the range of operation of the cutter. Therefore, the cloth is shifted and then held stationary until the section thereof thus brought within the range of operation of the cutter is exhausted or reduced to discs cut therefrom, 60 and then the cloth is shifted again, from time to time, until the entire length thereof has been operated upon in the desired manner. The cutter not only swings sidewise, 65 about a vertically disposed axis, but also

swings up and down about a horizontal axis, in the manner explained and shown in the drawings, and the manual control over the cutter is accomplished through the medium of the single handle 23 by which it is not only swung sidewise but also up and down. 70

What is claimed as the invention is—

1. In a cutting machine, the combination, of a rotary cylindrical cutter, having a limited range of operation, means for driving said cutter, means for movably holding sheet material at its edges in stretched out condition and in position to be engaged by said cutter, to cut discs from said material, means whereby the cutter is movable from one position 75 to another by the same power by which it is movable against and through the sheet material, and instrumentalities whereby to cause relative movement between the cutter and the sheet material by causing successive sections of the material to be brought within the range of operation of said cutter, to enable the cutter to engage any desired section of the sheet material. 80

2. A structure as specified in claim 1, said instrumentalities including means for manually moving the cutter up and down and laterally over the sheet material. 90

3. A structure as specified in claim 1, said instrumentalities comprising means for manually shifting the sheet material in the 95 plane thereof.

4. A structure as specified in claim 1, said instrumentalities comprising means for manually shifting the cutter from one place 100 to another on the sheet material, and comprising also means for shifting the sheet material. 105

5. A structure as specified in claim 1, said instrumentalities comprising means to provide a transverse axis about which the cutter is adapted to swing up and down, and comprising also means to form an axis about which the cutter is adapted to swing laterally. 110

6. A structure as specified in claim 1, in combination with a toothed ring to engage the section of material to be engaged by the cutter, and means to normally support said ring above the cutting edge of the cutter. 115

7. A structure as specified in claim 1, in combination with a swinging support which swings up and down, and means mounted on said swinging support to engage the section of material to be cut when the support is 120 swung down.

8. A structure as specified in claim 1, said instrumentalities comprising a movable support for the cutter, and said driving means being an electric motor mounted on said support and connected to said cutter, so that the motor remains in fixed relation to the cutter, and whereby the motor is moved around by the shifting of the cutter. 125

9. A structure as specified in claim 1, said 130

instrumentalities comprising a frame upon which to stretch the sheet material, guides for said frame, and means for moving said frame to shift the sheet material below the cutter.

10. In a cutting machine, the combination of cutting means, having a limited range of operation, and means for stretching and holding cloth in position below the cutter, comprising a movable frame and clamping bars with sharp points to pierce the cloth, so that the pressure of the cutter will not pull the edges of the cloth loose, and means to retain the clamping bars on the frame, said frame being movable at will to permit successive sections of the cloth to be brought within the range of operation of said cutter, and an actuator for moving said cutter about and also forcing it through the cloth.
11. A structure as specified in claim 10, in combination with means to positively move said frame with the cloth stretched thereon in the plane thereof to shift the cloth below the cutter.

25 12. A structure as specified in claim 10, means for adjusting the two sides of the frame toward and away from each other for different widths of cloth.

13. In a cutting machine, the combination
30 of a power driven cutter, means for manu-
ally moving said cutter over the material to
be cut, and means normally above the cut-
ting edge of said cutter and movable down-
ward from the cutter for engaging the ma-
35 terial around the cutter during the cutting
operation.

14. A structure as specified in claim 13, said cutter being cylindrical to cut out a disc from said material, and said holding means for engaging the material around the cutter comprising a ring having teeth to engage the material.

15. A structure as specified in claim 13, said cutting and engaging means having separate handles for the independent and manual control thereof.

16. In a cutting machine, the combination of a rotary cylindrical cutter, means for driving said cutter, means for holding sheet material in position to be engaged by said cutter, to cut discs from said material, and instrumentalities whereby to cause relative movement between the cutter and the sheet material to enable the cutter to engage any desired section of the sheet material, said instrumentalities comprising means to provide a transverse axis about which the cutter is adapted to swing up and down, and comprising also means to form an axis about which the cutter is adapted to swing laterally,

17. In a cutting machine, the combination of a rotary cylindrical cutter, means for driving said cutter, means for holding sheet material in position to be engaged by said

cutter, to cut discs from said material, and instrumentalities whereby to cause relative movement between the cutter and the sheet material to enable the cutter to engage any desired section of the sheet material, in combination with a toothed ring to engage the section of material to be engaged by the cutter, and means to normally support said ring above the cutting edge of the cutter. 70

18. In a cutting machine, the combination 75
of a rotary cylindrical cutter, means for
driving said cutter, means for holding sheet
material in position to be engaged by said
cutter, to cut discs from said material, and
instrumentalities whereby to cause relative 80
movement between the cutter and the sheet
material to enable the cutter to engage any
desired section of the sheet material, in combi-
nation with a swinging support which
swings up and down, and means mounted on 85
said swinging support to engage the section
of material to be cut when the support is
swung down.

19. In a cutting machine, the combination of a rotary cylindrical cutter, means for driving said cutter, means for holding sheet material in position to be engaged by said cutter, to cut discs from said material, and instrumentalities whereby to cause relative movement between the cutter and the sheet material to enable the cutter to engage any desired section of the sheet material, said instrumentalities comprising a movable support for the cutter, and said driving means being an electric motor mounted on said support and connected to said cutter, so that the motor remains in fixed relation to the cutter, and whereby the motor is moved around by the shifting of the cutter. 90 95 100

20. In a cutting machine, the combination of a rotary cylindrical cutter, means for driving said cutter, means for moving said cutter about and for forcing it through the cloth, means for holding sheet material in position to be engaged by said cutter, to cut discs from said material, and instrumentalities whereby to cause relative movement between the cutter and the sheet material to enable the cutter to engage any desired section of the sheet material, said instrumentalities comprising a frame upon which to stretch the sheet material, having adjustable means for clamping several thicknesses of material, serving to hold the cloth in position against pressure of said cutter, guides for said frame, and means for moving said frame in the plane thereof on said guides to shift the sheet material below the cutter. 105 110 115 120

shift the sheet material below the cutter.

21. In a cutting machine, the combination of a rotary cylindrical cutter, means for driving said cutter, means for holding sheet material in position to be engaged by said cutter, to cut discs from said material, and instrumentalities whereby to cause relative movement between the cutter and the sheet 125 130

- material to enable the cutter to engage any desired section of the sheet material, said instrumentalities comprising means to provide a transverse axis about which the cutter is adapted to swing up and down, and comprising also means to form an axis about which the cutter is adapted to swing laterally.
22. In a cutting machine, the combination of a rotary cylindrical cutter, means for driving said cutter, means for holding sheet material in position to be engaged by said cutter, to cut discs from said material, and instrumentalities whereby to cause relative movement between the cutter and the sheet material to enable the cutter to engage any desired section of the sheet material, in combination with a swinging support which swings up and down, and means mounted on said swinging support to engage the section of the material to be cut when the support is swung down.
23. In a cutting machine, the combination of a rotary cylindrical cutter, means for driving said cutter, means for holding sheet material in position to be engaged by said cutter, to cut discs from said material, and
- instrumentalities whereby to cause relative movement between the cutter and the sheet material to enable the cutter to engage any desired section of the sheet material, said instrumentalities comprising a movable support for the cutter, and said driving means being an electric motor mounted on said support and connected to said cutter, so that the motor remains in fixed relation to the cutter, and whereby the motor is moved around by the shifting of the cutter.
24. In a cutting machine, the combination of a rotary cylindrical cutter, means for driving said cutter, means for holding sheet material in position to be engaged by said cutter, to cut discs from said material, and instrumentalities whereby to cause relative movement between the cutter and the sheet material to enable the cutter to engage any desired section of the sheet material, said instrumentalities comprising a frame upon which to stretch the sheet material, guides for said frame and means for moving said frame to shift the sheet material below the cutter.
